SQUEEZE BOTTLE FOR PAINT OR THE LIKE

Benjamin Weiner, Stamford, Conn., assignor to Grow Chemical Corporation, New York, N.Y.

Filed Aug. 20, 1969, Ser. No. 18,778

Term of patent 14 years

Int. Cl. D9—01

U.S. Cl. D9—2

FIG.1

FIG.2

FIG.3

FIG. 1 is a perspective view of a squeeze bottle for paint or the like showing my new design;

FIG. 2 is a top plan view on an enlarged scale; and

FIG. 3 is an elevational view on the same scale as FIG. 1.

I claim:

The ornamental design for a squeeze bottle for paint or the like, as shown.
